TREATMENT OF HYDROCARBON OILS

Gustav Egloff and Jacque C. Morrell, Chicago,
Ill., assignors to Universal Oil Products Com-
pany, Chicago, Ill., a corporation of Delaware

No Drawing. Application January 12, 1934,
Serial No. 706,409

2 Claims. (Cl. 196—36)

This application is a continuation in part of our application Serial No. 518,879, filed February 27, 1931.

This invention relates more particularly to the refining of relatively low boiling hydrocarbon distillates at elevated temperatures, especially those distillates resulting from the conversion of relatively high boiling hydrocarbons at elevated temperatures and pressures.

10 In a more specific aspect the invention has reference to a process for refining cracked hydrocarbon oils of approximate gasoline boiling range under vapor phase conditions of treatment, using certain combinations of gaseous treating reagents and solid contact materials which will effect the desired degree of refinement.

The usual method of refining cracked distillates is to subject them to treatment with sulfuric acid and alkaline solutions, including 20 plumbite solutions consisting of litharge dissolved in alkaline solutions in various combinations of treatment, and subsequently to subject the acid treated product to redistillation, usually in the presence of steam.

25 The present invention permits the direct treatment of the hydrocarbon vapors from the cracking process, reducing the cost of reagents and eliminating the redistillation or rerunning operation, although it is within the scope of the invention to reevaporize the product in a subsequent operation and subject the vapors to treatment as described.

In one embodiment the invention comprises 30 subjecting hydrocarbon oil vapors, particularly cracked hydrocarbon oil vapors of approximate gasoline boiling range to treatment with sulfur trioxide and steam in the presence of selected solid metal salts which are of a substantially non-oxidizing character.

35 The salts which are preferred as contact materials to accelerate and modify the character of the treating reactions are certain sulfates, phosphates and chlorides, principally those of the so-called heavy metals. When employing sulfates

40 an equilibrium is established between the composition of the salt and the vapors of sulfur trioxide and steam so that substantially no chemical change occurs in the composition of the solid contact material, although there is some reduction of the sulfur trioxide on account of its oxidizing action upon the undesirable hydrocarbons and derivatives in the vapors undergoing treatment.

45 In the case of phosphates, many of these are

gradually decomposed by the action of the sulfur trioxide so that in the course of extended treatments the original phosphates are converted to a large extent into corresponding sulfates of varying degrees of basicity. The rate 5 and extent of such reactions of substitution will be determined by the mutual influence of a large number of operating factors such as temperature, pressure, relative concentration of reacting constituents, et cetera.

10 In the case of chlorides, the reaction of the sulfur trioxide thereon is usually more rapid so that the reactions of treatment are altered considerably due to the presence of the vapors of hydrochloric acid.

15 The following sulfates are adaptable to use in treatments conducted according to the invention:

Aluminum sulfate	20
Zinc sulfate	
Stannic sulfate	
Cupric sulfate	
Plumbic sulfate	
Mercury sulfate (basic)	
Nickel sulfate	25
Manganic and manganous sulfates	
Cadmium sulfate	

Under the preferred conditions of temperature which will be given hereinafter, it has been found to be preferable to use only sulfates which are 30 solid under the conditions of treatment. This usually eliminates the use of sulfates of cobalt and of chromium on account of their tendency to flux. A sulfate of vanadium known as vanadyl sulfate finds application in some instances.

35 The following phosphates may be employed:

Aluminum phosphate	
Zinc phosphate	
Lead phosphates (includes a pyrophosphate)	40
Ferric phosphate	
Nickel phosphate	
Chromium phosphate	
Manganese phosphates	
Vanadium pyrophosphate	45
Cadmium phosphate	

45 In the phosphate group may also be mentioned phospho-molybdates and phospho-tungstates.

The number of chlorides which may be successfully employed as contact materials is somewhat 50 limited by practical considerations as to cost, melting point and volatility. Many compounds which would be utilizable in liquid phase treatments are ruled out by melting point and boiling point considerations. The following chlorides

55

may be used under properly regulated operating conditions:

5   Zinc chloride
      Cadmium chloride
      Cupric chloride
      Manganese chloride
      Molybdenum chlorides (di, tri and tetra)
      Chromic chloride

It is within the scope of the invention to employ 10 as solid contact materials single chemical compounds selected from the above mentioned groups or mixtures of the same which may be found to give good treating effects upon any given distillate which may be treated. It is to be understood 15 that each specific contact substance or mixture of different chemical compounds will exert its own peculiar catalytic or chemical influence upon the course and extent of the treating reactions so that the different contact materials are not to be 20 considered as exact equivalents though they may assist in producing somewhat analogous treating effects.

Of the compounds mentioned as being utilizable some may be artificially prepared and some 25 may be used as minerals as they are mined.

In applying the process of the invention to practice any suitable equipment may be employed which will permit the contacting of the hydrocarbon vapors and the sulphur trioxide and steam 30 with the metal salts; for example, a suitable tower or chamber packed with a selected salt or mixture of salts may be employed following the fractionator of a cracking system, feeding the sulphur trioxide and steam directly to the tower concurrent 35 with the flow of the hydrocarbon vapors, thus permitting contact of the sulphur trioxide and steam and hydrocarbons to be treated with the solid materials. Sulphur trioxide from any suitable source, alone or in combination with steam, 40 may be introduced directly into the tower or treating vessel containing the contact salts. In lieu of direct packing of the tower or treating vessel with the metal salts an inert filling material such as Raschig rings, firebrick, crushed rock, 45 gravel, crushed ceramic material, and the like, suitably mixed or coated with a salt, may be employed. Similarly, any device which permits the efficient contacting of the vapors undergoing treatment with salts may be employed.

50   The tower or treating vessel containing the contact material may be directly connected to a cracking unit or to a rerun or redistillation unit so that the vapors arising therefrom may be treated in the manner described.

55   It has been found desirable to neutralize the distillate immediately after condensation either by passing the condensate directly through a body of alkali such as a solution of caustic soda or by washing the distillate free of sulphur oxides with 60 water and/or alkalies, such as a solution of caustic soda, ammonia, or the like. The neutralizing agent may also be introduced into the vapor line leading to the condenser or into the condenser itself.

65   The amount of sulphur trioxide employed may vary from a fraction of a pound to several pounds, based on a barrel of hydrocarbon distillate treated.

70   Various temperatures of treatment may be employed, for example, from 250-600° F., more or less, and the pressures may be sub-atmospheric, atmospheric, or superatmospheric. While the results may vary with the temperatures employed, the pressures and temperatures are chosen so that the hydrocarbons are treated substantially 75 in the vapor phase.

In order to reduce the intensity of the reaction the sulphur trioxide may be admixed with an inert gas and a flue gas carbon dioxide and the like and may be introduced at various successive points in the treating tower.

5   The effects produced upon oil vapors, particularly those produced from the cracking of heavy hydrocarbon oils by the use of gases and solid contact substances characteristic of the invention are in general those of polymerization or condensation of relatively highly unsaturated hydrocarbons or their derivatives, particularly their sulfur derivatives. The net result is the controllable elimination of groups of compounds which are readily polymerized under oxidizing conditions to 10 form substances of a gummy or resinous nature which are undesirable in motor fuel.

The treatment herein described may constitute the sole refining action on the oil, or it 15 may constitute one step in a series of refining steps. It may be preceded by the usual treatments with refining agents such as sulphuric acid, caustic soda, plumbite, filtering earth or the like, and may be succeeded by any combination 20 of the above refining agents, followed, if desired, by distillation.

25   As specific examples of the operation of the process of the invention and of the results obtained by its use, the following may be given:

(1) A California cracked distillate of approximately 30 motor fuel boiling range may be vaporized and subjected to treatment with a mixture of sulfur trioxide and steam during the passage of the vapors in the downward direction through a stationary contact mass consisting of a mixture of a finely divided zinc sulfate supported on fuller's earth, the weight of the earth being approximately four times that of the salt. The sulfur trioxide may be used in an amount equivalent to approximately three pounds per barrel 35 of oil. The untreated product may show a gum content of approximately 500 mgs. per 100 cc. and have a reddish brown color, with a sulfur content of approximately 0.45%. The treated product after suitable separation from spent reagents, neutralizing with alkalies and washing with water, may show a gum content of approximately 30 mgs. and a color of +25 on the Saybolt scale. The sulfur content may be found to be as low as 0.2%. 40

(2) In the case of a mixed Mid-Continent and West Texas cracked distillate treated with approximately the same amounts of reagents, the gum content may be reduced from 300 mgs. to 20 and the color raised from a light amber to 55 approximately 25 on the Saybolt scale. The sulfur content may be reduced from 0.4% to approximately 0.15%. 45

(3) The process of the invention is particularly suitable to the treatment of cracked distillates produced from California oils. In some cases the untreated distillates may contain 60 mgs. of gum and have a dark reddish color while the treated distillates may have a gum content of only 40 mgs. and a color of 25 to 30 on the Saybolt scale. The sulfur content may be reduced from 0.5% to 0.15%. 65

70   The foregoing description and examples have disclosed a process applicable to the treatment of hydrocarbon oil vapors which has a wide applicability and is capable of great variation in the methods of operation and the amounts of reagents employed. Therefore, the specific cases cited are not to be construed in a limiting sense 75 upon the broad scope of the invention as many 75

other modifications can be used and examples of results therefrom given.

We claim as our invention:

1. A process for refining hydrocarbon oil which comprises subjecting said hydrocarbon oil in vapor form to the action of sulphur trioxide and steam in the presence of zinc sulfate.

2. A process for refining hydrocarbon oil which comprises subjecting said hydrocarbon oil in vapor form to the action of sulphur trioxide and steam in the presence of finely divided zinc sulfate and fuller's earth.
